UNITED STATES PATENT OFFICE

1,986,608

NONMETALLIC BEVELED GEAR WHEEL

Guy O. Small, Lynn, Mass., assignor to General
Electric Company, a corporation of New York

Application October 1, 1931, Serial No. 566,280

2 Claims. (Cl. 74—445)

The present invention relates to non-metallic beveled gear wheels and especially to such gear wheels formed from woven fabric, such as cotton duck for example, united by an adhesive binder 5 such as a phenolic condensation product or other artificial resin.

One object of my invention is to provide an improved construction in a non-metallic beveled gear wheel formed from woven fabric which is capable of being readily manufactured at a low cost and in which the layers of fabric run in a direction to give the greatest strength to the teeth, each layer of fabric that sustains stresses in the gear tooth being anchored in the body of 10 the material below the root of the tooth.

A further object of my invention is to provide an improved method of manufacturing a gear wheel of this type or a blank for such a gear wheel.

For a consideration of what I believe to be novel 20 and my invention, attention is directed to the following specification and the claims appended thereto.

In the drawing, Fig. 1 shows a fabric which has been treated with an uncured adhesive and rolled 25 to form a cylinder; Fig. 2 shows a step in carrying out my improved method; Fig. 3 shows a completed structure, the blank before the teeth are cut thereon being shown at the right hand portion of the view and the blank with teeth cut 30 thereon being shown at the left hand portion of the view, and Fig. 4 shows another form of bevel gear wheel.

In carrying out my invention I take a strip of woven fabric such as cotton duck for example, 35 which has been treated with uncured adhesive, for example, an artificial resin, such as a phenolic condensation product, and wind it snugly on an arbor to form a roll 1 as shown in Fig. 1. The strip may be of a width equal approximately to the 40 axial length of the finished gear wheel and the central opening 2 of the roll may have a diameter equal approximately to the size of the diameter of the bore desired through the hub or center of the gear wheel. I then place the roll in a suitable 45 die comprising a central member 3 and a surrounding ring 4 between which the roll fits snugly and compress it by means of a die member 5 which enters the space between the members 3 and 4. As will be clear, this compresses the roll in an axial 50 direction, the fibres of the roll crinkling as shown in the right hand portion of Fig. 3. It will be understood that the roll is compressed in a suitably

heated press to cure the adhesive under heat and pressure, this being a well known step in the curing of such an adhesive, that is, converting it into its hard, infusible, insoluble state. After the adhesive is cured, the roll is removed from the press, 5 thereby providing a blank for a bevel gear wheel. The blank is in the form of a cylinder of woven fabric united by an adhesive, the successive layers of the cylinder extending axially thereof. The teeth for the beveled gear are then cut in one end 10 of the blank as is indicated at 7 in Fig. 3, the teeth being cut to extend at an angle such as to give the desired bevel.

My invention is well adapted to the manufacture of beveled gear wheels of relatively large diameter, wherein a ring or cylinder of non-metallic material is supported on a metal hub or spider. This form of my invention is shown in Fig. 4 15 wherein 8 indicates a metal hub or spider provided with an annular recess 9 in which is suitably fixed a ring or cylinder 10 of non-metallic material made in accordance with my invention and provided with beveled teeth 11.

With the above construction it will be seen that in the finished gear wheel the layers of fabric 20 extend transversely of the teeth and from the root to the tip so that the edges of the layers of fabric are exposed to the working or contacting surfaces of the teeth and each layer is anchored in the body of the gear wheel. This gives the maximum 25 strength to the teeth. This advantageous arrangement of the layers in the teeth is obtained in a relatively simple manner and by a method of manufacture readily carried out. By my method of manufacture I am enabled thus to provide satisfactory beveled gear wheels at relatively low cost. 30

What I claim as new and desire to secure by Letters Patent of the United States is:

1. A beveled gear wheel comprising a cylinder 40 formed entirely of successive concentric layers of woven fabric, each layer having its width extending axially of the cylinder, said layers being united by an adhesive, and bevel teeth cut at an angle in one end of the cylinder.

2. A beveled gear wheel comprising a cylinder 45 formed entirely of a continuous strip of woven fabric wound concentrically to form a cylinder with the width of the strip extending axially and an adhesive uniting successive layers of the fabric, and bevel teeth cut at an angle in one end of the 50 cylinder.

GUY O. SMALL.
